UNITED STATES PATENT OFFICE

172,241

HUB CAP

John W. Mason, Detroit, Mich., assignor to Motor
Wheel Corporation, Lansing, Mich., a corpora-
tion of Michigan

Application December 28, 1953, Serial No. 28,245

Term of patent 7 years

(Cl. D14—30)

To all whom it may concern:

Be it known that I, John W. Mason, a citizen of the United States, residing at Detroit, in the county of Wayne, and State of Michigan, have invented a new, original, and ornamental Design for Hub Cap, of which the following is a specification, reference being made to the accompanying drawings, forming part thereof.

Fig. 1 is a front elevational view of a hub cap, showing my new design.

Fig. 2 is a side elevational view of the same.

Fig. 3 is a section along the line 3—3 of Fig. 1.

I claim:

The ornamental design for a hub cap, as shown.
